UNITED STATES PATENT OFFICE

2,544,835

AUTOMATIC BEAD MAKING MACHINE

Eugene C. Healy, Pawtucket, R. I.

Application March 23, 1948, Serial No. 16,542

4 Claims. (Cl. 153—73)

1

This invention relates to an automatic beading machine and the primary object of the invention is to provide a device that will quickly and efficiently provide a finished beaded strip within a short space of time.

Another object of the invention is to provide a simple structure capable of carrying out the process in a single step and one which is as efficient in operation as any of the more complicated devices.

Features of the invention concern a pair of oppositely arranged dies, means to rotate the said dies and compress them together while being rotated, and means to quickly separate the device when the formed beads are ready to be removed.

A further object of the invention will become readily apparent from the description which follows, taken together with the drawings, in which:

Figure 1 is a side elevation of the device of the invention;

Figure 2 is a top plan view of the device shown in Figure 1;

Figure 3 is a transverse sectional view taken along the line 3—3 of Figure 1;

Figure 4 is a horizontal sectional view of the invention, taken substantially along the line 4—4 of Figure 1;

Figure 5 is an enlarged fragmentary view of the beads in the process of formation;

Figure 6 is an enlarged sectional view of the beads being formed;

Figure 7 is an enlarged sectional view of the beads formed with the dies pressed together;

Figure 8 is a perspective view of a sample bead, and

Figure 9 is a modification of the die pressing means.

The device of the invention is indicated generally at 10 and includes a flat support or table 12 supported on legs 14. Die block 16 is supported on table 12 by means of stanchions 18 containing lateral flanges 20 which are bolted to table 12 at 22. Stanchions 18 integrally mount a pair of cam rings 24 which include cam members 26 spaced around the inner periphery thereof. Four members 26 are shown, though it is obvious that the total number may vary. (Figure 3.) Each cam ring 24 is made of two semi-annular rings 28 and 30, each terminating in opposed flanges 32. Retained between flanges 32 is a coil spring 34 urging the cam rings apart. Hydraulic means, indicated at 36 and connecting to a suitable source of supply (not shown), is mounted on flanges 32 of each cam ring segment 28, to close the cam rings 26, in a manner to be more fully

2

explained. Since the operation of the hydraulic means is conventional, it is believed that no further description of the operation thereof is necessary. Cam ring 24 is hinged at 37 to pivotally retain the segments 28 and 30 thereof together.

Die 16 consists of two semi-cylindrical members 38 and 40 in oppositely disposed relation. A plurality of bead forming recesses 42 are formed along the diametrical surfaces thereof. On each 10 extremity of dies 38 and 40 are longitudinal counterbores 44 which engage with locking pins 46 extending transversely from end plates 48 and 54. Each end plate includes a laterally extending shaft 50, while plate 48 contains an integral pulley 52 mounted at the outer end of shaft 50. Both shafts are axially apertured at 56 along the lengths thereof and are supported by stanchions 60 bolted at 62 to table 12. A work stock 58 is inserted into the die through aperture 56.

20 Referring to Figure 3, die members 38 and 40 are transversely counterbored at 64, 66 in apertured alignment. A spring 68 is seated in bore 66 of die member 40 to urge outwardly a peg 70 located in and extending beyond bore 64.

25 A motor 72 is connected by means of pulley 74 on drive shaft 76 to pulley 52 by means of pulley belt 78.

From the above, the operation of the device becomes readily apparent. Die members 38 and 30 40 are normally urged apart by means of springs 68 and pegs 70. A bead-making stock is then inserted through aperture 56 and motor 72 is started to rotate the die 16 by engagement of pins 46 in bores 44. Cams 26 on cam ring 24 give

35 a hammering action on die block 16 and pressure is simultaneously applied to hydraulic means 36 to compress spring 34 until the closed position shown in Figure 7 is attained. When the beads are completely formed, pressure on cam ring 24 is shut off and the rotation of die 16 is stopped.

40 In Figure 9 is illustrated a modification of the pressure means shown in Figure 3. Flanges 62 and 64 are similar to flange 32 shown in Figure 3. Flange 64 is apertured at 66 to receive therethrough a threaded bolt 68 pivoted at 70 in flange 62, retaining spring 72 between flanges 62, 64 in diverging relation. A wing nut 74 is rotated on bolt 68 to overcome the pressure of spring 72.

45 It is to be understood that the invention is not to be limited to the identical construction disclosed in the drawings, since it is obvious that various changes and modifications might be 55 made therein without departing from the spirit

and scope of the invention as defined in the claims.

Having described the invention, what is claimed as new is:

1. In an automatic beading machine, a pair of oppositely disposed dies, means on the dies to form beads, springs secured in one die, peg means in the other die engaging said springs, a cam ring encircling said dies, said cam ring being split and having a hinge connection on one side and opposing terminal flanges on the side remote from said hinge connection, and compression means engaging said flanges for urging them together.

2. In an automatic beading machine, a pair of oppositely disposed dies, means on the dies to form beads, springs mounted in bores in one of said dies, peg means in the other of said dies engaging and compressing said springs, a cam ring encircling said dies and comprising opposing segments releasable, hinged together for moving the segments of said cam ring toward each other, thereby releasably pressing said oppositely disposed dies together.

3. A machine according to claim 1 wherein

5 said dies are elongated and including means to rotate the dies about a longitudinal axis.

10 4. A machine according to claim 1 wherein said dies are elongated and including means to rotate the dies about a longitudinal axis and a hydraulically operated clamp exteriorly and frictionally engaging said dies, whereby the dies while being rotated can be made to approach and to retract from each other due both to the action of the cams on said cam ring acting directly on the dies as well as the actuation of the hydraulic clamp.
